UNITED STATES PATENT OFFICE.

KATIE WILDBERGER, OF MENNO, SOUTH DAKOTA.

RECEPTACLE ACTUATOR.

Application filed August 25, 1922. Serial No. 584,208.

To all whom it may concern:

Be it known that I, KATIE WILDBERGER, a citizen of the United States, residing at Menno, in the county of Hutchinson and State of South Dakota, have invented new and useful Improvements in Receptacle Actuators, of which the following is a specification.

The object of my said invention is the provision of a simple, easily operated and efficient receptacle actuator especially adapted to foot-power churning susceptible of being worked by a woman with so little effort that the operator can if she so elects read or do fancy work or mending while actuating the churn.

To the attainment of the foregoing, the invention consists in the improvement as hereinafter described and definitely claimed.

20 In the accompanying drawings, forming part of this specification:—

Figure 1 is a front elevation of the churn constituting the best practical embodiment of my invention that I have as yet devised.

25 Figure 2 is an end elevation of the same.

Figure 3 is a top plan view of the churn.

Figure 4 is an enlarged diametrical section of the churn body.

Figure 5 is an enlarged detail view of 30 one of the journal bearings comprised in the churn.

Similar numerals of reference designate corresponding parts in all of the views of the drawings.

35 As will be readily understood by comparison of Figures 1 and 3 my novel churn actuator takes up but little floor space and hence can be conveniently stored or placed out of the way when not in use. Among 40 other elements the churn comprises a rotary body 1, preferably of metal and tinned at its inner side. The said body is provided with a drain opening 2 normally closed by a plug 3 or other appropriate closure means,

45 and at its upper end the body has an exteriorly threaded neck 4. This neck 4 constitutes an abutment for a transparent disk 5, preferably of glass, through which the operator can view the contents of the body

50 and note the progress made in the butter-making operation. The said disk 5 is removable as is also the threaded and flanged disk-retaining annulus 6 which is of appropriate metal and is provided with radial projections 7 so that it can be powerfully turned in either direction on the neck 4.

An annular gasket 8 of rubber or other compressible material is arranged about the base of the neck 4, Figure 4, to seal the joint and cushion the annulus at that point 60 when it serves to hold the disk 5 in liquid-tight manner against the end of the neck 4.

In addition to the body 1 characterized as described, the churn comprises a rotary frame 9 in which the body is brazed or 65 molded or otherwise permanently fixed, the said frame 9 surrounding the body at an intermediate point in the length thereof.

Fixed with respect to and extending radially in opposite directions from the 70 frame 9 are shaft portions 10 and 11 each of which terminates at its outer end in a ball 12, Figure 5. At an intermediate point in its length the shaft portion 11 is provided with an integral crank 13. The 75 said balls 12 at the outer end of the shaft portions 10 and 11 are journaled in socket bearings 14 at the upper ends of frame standards 15, one of the said standards 15 and a supplemental short standard 15^x fixed 80 to and braced by an interposed horizontal rod 16, arranged below and in parallelism with the shaft portions 10 and 11. At their lower ends the frame standards 15 and 15^x are provided with broad feet 17 to lend 85 stability to the structure; and it will also be noted that the supplemental short frame standard 15^x is connected to one of the standards 15 by a low horizontal brace bar 18 which is fixed to the said standards or 90 to the feet thereof as shown. The rod 16 together with the shaft 20 arranged in alinement therewith forms an effective bracing member directly connecting the standards 15 together, and the shaft section 95 20 of this bracing member additionally serving to support the treadle 21 for rocking movement.

Journalized in sockets 19 on one standard 15 and the short standard 15^x are balls at 100 the ends of a rock shaft 20 to which is approximately fixed a treadle 21 with an end extension 22 in the form of a journal as illustrated.

The ball and socket joints described are 105 materially advantageous inasmuch as in virtue of the same, the several shaft portions 10, 11 and 20 are enabled to retain the standards in proper relation without the assistance of extraneous means; it being 110 understood in this connection that in assembling the elements of the churn, the sockets

are spun or otherwise positioned about the balls.

Pivottally mounted on the crank 13 and journal extension 22 are couplings 23 and 24, respectively, and interposed between and connected to the said couplings is a coiled spring pitman 25 which is advantageous because its elasticity contributes to the easy running quality of the churn after the body 10 1 is initially rotated by hand to impart momentum thereto.

In order to retain the body 1 in upright position incident to the pouring of cream into the body or the lifting of butter therefrom I provide the eye 26 on the body, and the loosely-connected hook 27 on the adjacent socket bearing 14; said hook being engaged with the eye 26 at the time stated and being permitted at other times to rest 20 idly on the said socket bearing.

It will be readily apparent from the foregoing that I have provided an easy running and efficient churn actuator of simple and durable construction, and one that is susceptible of being easily and thoroughly cleaned, and is adapted to be readily moved from one point to another which in its final analysis includes only four main parts, the standards 15 carrying feet 17, the receptacle receiving member 9 with the shaft portions 10 and 11, and the bracing member 16 with its rotary section 20 supporting the treadle having a connection 25 with the crank 13.

I have entered into a detailed description 35 of the construction and relative arrangement of the parts embraced in the present and preferred embodiment of my invention in order to impart a full, clear and exact understanding of the said embodiment. I 40 do not desire, however, to be understood as confining myself to the specific construction and relative arrangement of parts inasmuch as in the future practice of the invention various changes and modifications may be 45 made such as fall within the scope of my invention as defined in my appended claim.

Having described my invention, what I claim and desire to secure by Letters-Patent, is:—

A receptacle actuator including a pair of end standards having supporting feet, a rotary work carrying member having shaft portions extending in alined relation therefrom, one of said shaft portions being 55 formed with a crank, and the ends of said shaft portions being journaled in the upper end of the standards, a brace member connecting said standards having a section adapted for oscillating movement, a treadle 60 mounted on said oscillating section, and a connection between the treadle and crank for rotating the crank and work carrying member in the oscillation of the treadle.

In testimony whereof, I affix my signature.

KATIE WILDBERGER.
